INVENTOR

WILLIAM G. RAU

BY *Alpheus Fay*

ATTORNEY.

UNITED STATES PATENT OFFICE

WILLIAM G. RAU, OF LOUISVILLE, KENTUCKY

NECKTIE HOLDER

Application filed April 4, 1929. Serial No. 352,433.

My invention relates to attaching devices for neckties, and its object is to provide a very simple, inexpensive and easily applied means for holding the knot of the necktie, 5 which is the kind that is tied when the wearer is putting the tie on, and to hold this knot snugly up over the collar button, so that the tie not only does not become untied, but does not slip down, revealing the button.

10 I accomplish this object by the device illustrated, for example, in the accompanying drawing, in which—

Figure 1 is a front perspective view of part of a collar and part of a necktie thereon, 15 having my improved device applied thereto, the device, which lies behind the tie, being indicated by solid lines, as are also the button and the pin associated therewith; while the tie is shown by dotted lines;

20 Fig. 2 is a partial sectional view of the shirt front, its neck band, and the collar attached thereto, the necktie being in side elevation, and my device being shown in section on the button and pinned to the tie as in Fig. 1;

Fig. 3 is a front view of the device; and

Fig. 4 is a section on the plane of the line 4—4 of Fig. 3.

The device as herein illustrated comprises 30 a strip 1 of elastic material, such as sheet rubber or elastic webbing, preferably narrower in its middle 2 than in its end parts 3 and 4, both of the latter being perforated. The upper end part 3 has its perforation preferably in the form of a small button hole 5, and in the perforation of the lower end part 4 is an eyelet 6.

The necktie 7, which is of the "four-in-hand" style, is tied in the usual manner and 40 drawn partly up into the collar 8. My device then is applied by buttoning the upper end part 3 onto the collar button 9, after which the tie 7 is drawn completely tight and up over the button 9, as usual. Then the free 45 parts of the necktie 7 are lifted, and the device is stretched moderately and its lower end part 4 is held to the back of the tie 7 shortly below the knot thereof as shown in Figs. 1 and 2, and a pin 10 is inserted up through the 50 eyelet 6 of the part 4 and into the fabric of

the back of the tie 7, pinning the lower end part of the device to the tie just below the knot thereof and resulting in the elastic strip 1 pulling up constantly on the necktie and preventing the downward displacement 55 thereof as before alluded to. The device thus accomplishes its object without being seen from the front; and, as here shown, the pin 10 also is entirely concealed.

However, it will be understood that the pin 60 may be inserted to show its head at the front of the tie, and have an ornamental head, like the usual stick pin. In this case, the pin may be longer, and my device may be longer, or may be stretched farther, accordingly. But 65 it also will be understood that the device may be made shorter, so that the pin enters the back of the knot, fastening the knot against becoming untied.

The construction of the device itself may 70 be varied as to material; for example, elastic cord may be formed with loops to serve as the end parts 3 and 4, or the lower part may have the pin or equivalent fastening means permanently attached thereto, to be caught 75 in the tie. Other modifications may occur without departing from the scope and spirit of my invention, which is defined in the following claims.

I claim:

1. In combination with a collar, fastening means for said collar, and a necktie in front of said fastening means, an elastic tension element having one end part engaging said collar-fastening means and extending down 80 behind said necktie, and a pin extending through a part of said necktie and then through the opposite end part of said tension element and then into a part of said necktie, 85 whereby said tension element holds said necktie up in front of said collar-fastening means.

2. In combination with a collar, a button for said collar, and a necktie in front of said button, a tension element having a buttonhole in one end part, receiving said button, and having an eyelet in its other end part, at least an intermediate part of the length of said element being longitudinally yielding, and a pin extending through a rear 95 part of said necktie and then through said 100

eyelet and then into another rear part of said necktie, fastening said other end part of said element to said necktie whereby said element, by its engagement with said button, holds said necktie up in front of said button.

3. A necktie holder comprising a flat strip of elastic material having its opposite end parts wider than its intermediate part, whereby said intermediate part is adequately yielding and said wider end parts are of adequate strength to permit of firm fastening to a collar button and to a rear part of a necktie to hold said necktie up in front of said button.

4. A necktie holder comprising an elongated element having its opposite end parts wider than its intermediate part, and means whereby said opposite end parts are connected to a collar button and the rear part of a necktie, respectively, said intermediate part being elastic longitudinally.

WILLIAM G. RAU.
